UNITED STATES PATENT OFFICE.

HERBERT A. PHILLIPS AND JOHN G. STAMM, OF CLEVELAND, OHIO.

DESIGN FOR AN EMBLEM, INSIGNIA, OR SIMILAR ARTICLE.

52,490.

Specification for Design.

Patented Sept. 24, 1918.

Application filed June 27, 1918. Serial No. 242,298. Term of patent 7 years.

To all whom it may concern:

Be it known that we, HERBERT A. PHILLIPS and JOHN G. STAMM, both citizens of the United States, residing at Cleveland, in the county of Cuyahoga and State of Ohio, have invented a new, original, and ornamental Design for an Emblem, Insignia, or Similar Article, of which the following is a specification, reference being had to the accompanying drawing, forming part thereof.

The figure is a plan view of an emblem, insignia or similar article showing our new design.

We claim:

The ornamental design for an emblem, insignia, or similar article as shown.

HERBERT A. PHILLIPS.
JOHN G. STAMM.
